2 Claims. (Cl. 177—327)

This application is a division of Serial No. 277,288, filed June 3, 1939.

The invention relates to a vehicle rear signal, and its object is to enable the driver of a following car to judge his distance from the leading car.

According to the invention the rear light has at least two light sources so spaced apart that at distances beyond a certain range they are not separately distinguishable but appear as a single patch of light.

An example of the device constructed according to the invention is shown in the accompanying drawing, in which

Fig. 1 shows one form of construction in perspective, and

Fig. 2 a section on the line A—B through the device of Fig. 1.

In the one wall of the device 1 there are four windows 2, which receive their light indirectly by 20 a common lamp. For this purpose the lamp is screened by a screen 3 from the one wall of the casing 1, whereas the other wall 4 of the casing 1 has a plane paraboloid shape and is provided with a light dimming cover. The windows 2 emit light to the rear of the vehicle, but this light is of very moderate brightness.

The two windows 2 on each side of the vertical centre plane of the casing 1 are so spaced that they are separated only by a narrow plane 14, but between the inside windows 2 there is a much wider plane 14.

With a lamp of suitable power, and a reflector of suitable brightness, the four windows are not separately distinguishable at a distance of about 100 m. At some range between this and, say, 60 m., the division due to the wide panel 14 becomes visible, and the arrangement is seen as two patches of light.

Further reduction of distance, say to 30 or 40 m., enables the four windows to be distinguished as four separate patches of light.

This is of great assistance in enabling the driver of a following car to judge his distance from the leading car.

It will be understood that the sub-division due to the outer panels 14 may be dispensed with, but in that case the equipment affords an index to only one range. Similarly it will be understood that the sub-division may be carried further, with panels of appropriate widths enabling additional stages of approach to be recognized. For obtaining windows of different degrees of luminosity separate panes of glass of varying degrees of

transparency may be used for the windows, or provision may be made for sliding in additional panes, or there may be rotatable holders carrying panes which can be used alternatively, by rotating the holders.

The reflector 4 shown in the drawing is of plane-paraboloid shape, so that it has a line focus instead of a point focus, with the lamp filament in this focus, so that the windows are uniformly illuminated. Uniformity of illumination can also be secured by differently coloring the parts of the reflector at different distances from the windows, the part at the centre being darkest.

In connection with the device 1 can be provided a usual stop light 9 and a rear light 6. At the bottom of a casing 5, having the openings 6 and 9 there is an opening with a lens 7 for illuminating the number plate 8 by means of a lamp in the casing 5 behind the opening 6.

Between the casings 1 and 5 there is a spindle fixed to a flap 10, which has a flange 11 with a colored window 12 for dimming the number plate light.

The flap 10 is so arranged on the casings 1 and 5 that it covers in its one position the device 1 and in the other position the windows 6, 7, 9 of the rear light arrangement. The flap 10 has in this case only the window 12 which is of course colored.

What I claim is:

1. A rear light arrangement for a road vehicle providing means for estimating the varying distances of an observer from the rear end of the vehicle at relatively close range, said arrangement comprising a single source of light, a light impervious screen disposed on one side of said source of light, said screen being provided with at least two spaced apart windows of substantially rectangular shape, means preventing direct light from said source from falling through said windows, and a reflector disposed on the opposite side of said source, said reflector being adapted and arranged to illuminate the areas of said windows uniformly with reflected light from said source.

2. A rear light arrangement, as claimed in claim 1, in which the surface of said reflector is so arranged as to have better reflecting qualities at points farther removed from the light source than at points nearer the light source, thus tending to compensate for the smaller amount of light reaching the farther points and producing a substantially uniform illumination of said windows.

FRIEDRICH RICHARD DIETRICH.
